UNITED STATES PATENT OFFICE.

GEORGE B. COLEMAN, OF SAN FRANCISCO, CALIFORNIA, ASSIGNOR, BY DIRECT AND MESNE ASSIGNMENTS, TO MAJIK ELECTRIC APPLIANCE COMPANY, OF SAN FRANCISCO, CALIFORNIA, A CORPORATION OF CALIFORNIA.

PORTABLE GENERATING SET.

Application filed May 7, 1921. Serial No. 467,770.

To all whom it may concern:

Be it known that I, GEORGE B. COLEMAN, a citizen of the United States, and a resident of the city and county of San Francisco and 5 State of California, have invented a new and useful Portable Generating Set, of which the following is a specification.

The present invention relates to electric generators and more particularly to a small 10 portable generator.

It is an object of the present invention to provide a compact, and simple self-contained electric generating apparatus in which the rotor of the electric generator is driven by 15 means of a main spring associated by means of a transmission mechanism with the generator.

A further object of the invention is to provide a small, conveniently arranged and 20 carried, generator for the production of electricity to furnish power for energizing small electric appliances.

Another object of the invention is to provide an organized, self-contained generating 25 set having a main driving spring adapted to be manually or otherwise wound for the storage of the energy to be transmitted at a predetermined rate of speed for the rotation of the rotor of the associated generator. 30 And, in this connection, it is further an object to provide means for the controlling of the operation of the generator as may be desired by the stored energy of the spring.

The invention possesses other objects and 35 features of advantage, some of which, with the foregoing, will be made manifest in the following description of the preferred form of the invention which is illustrated in the drawings accompanying and forming part of 40 the specification. It is to be understood that it is not intended to limit the invention to the embodiment shown by the said drawings and description as variations may be adopted within the scope of the invention as 45 set forth in the claims.

The invention may be embodied in a variety of structures and is shown in the present case, in Fig. 1 as embodied in the form of a small flash lamp, to be conveniently 50 carried on the person, or in any suitable receptacle, while, in Fig. 2 the invention is shown as embodied in the form of a desk or table lamp. However, these show

only some of the various adaptations of the invention.

In its preferred form the invention consists of a tubular shell of suitable material and proportions, in which there is mounted a main spring adapted to be manually or otherwise wound or tensioned, and contiguous to which there is disposed a multiplication transmission gearing, the speeded up driving element of which is connected to the rotor of a generator also arranged in the shell. Means are provided for controlling, at will, driving of the rotor of the generator by the stored energy in the spring.

The embodiments of the invention here shown include a shell or housing 2, within which is arranged a main spring 3, preferably of the spiral type, and whose inner end is connected to one of the shafts of a suitable form of clock-work 4 having a pinion shaft 5 connected as by a coupling 6 to a shaft 7.

The shaft 7 forms the driving connection between the clock-work and a suitable form of electric generator arranged within the shell 2 and which, in the present case, has a rotor or armature 8 the pole pieces 9 of which are arranged in a common plane perpendicular to the axis of rotation of the armature and shaft 7. The pole pieces 9, a suitable number of which may be employed, sweep in a plane parallel to poles of a fixed field element 10 of the generator. Current is collected from the generator, while it is in operation, by lead wires 11 and 12 associated with brushes 13 bearing against a disk-like commutator 14 of the rotor 8. The lead wires 11 and 12 are shown in Fig. 1 as connected to an electric lamp receptacle 15 in which is mounted a lamp 16, behind a lens 17, mounted on one end of the shell 2.

Various forms of mechanism may be utilized for winding the main spring to store therein the desired energy for driving the rotor of the generator and in Fig. 1 the outer end of the main spring 3 is attached to a cover or cap 20 rotatively mounted on the contiguous end of the shell 2 and held against axial movement. To wind the spring 3, the end cap 20 is rotated about the shell 2, suitable means being provided to lock the cap 20 against retraction and unwinding of the spring. Such a means may

consist of a ratchet dog 21, interposed between the cap 20 and the shell 2 and which is operative to permit the cap to be freely rotated in one direction and prevent rotation thereof in the opposite direction.

Since the main spring 3 has a tendency to instantly rotate the rotor of the generator when the spring is placed under tension it is desirable to provide suitable means for 10 locking the operating mechanism against action except as may be desired. To that end a simple brake device is employed and may consist of a brake lever 22 arranged in the shell to engage a contiguous portion of a 15 rotating part as for instance the rotor.

The brake is normally effective to restrain the operation of the generating mechanism and may be held in action as by a spring 23. In order to release the restrained driving 20 mechanism, so that the rotor may be turned, a push button 24 is arranged to be conveniently actuated and disengage the brake 22 from restraining action.

The invention may be readily adapted in 25 the form of a table lamp the shell of which may be provided with any suitable attractive and ornamental design as shown in Fig. 2. Since it is desirable, when the invention is employed as a table lamp to provide for 30 the storage of energy in a spring of such size that the generator can be operated for a considerable period of time, as for example two or three hours, a different form of winding mechanism for the spring may be utilized, such, for instance, as a crank 30 35 mounted on the base portion 2^a of the shell and carrying a pinion 31 engaging a master gear 32 to which one end of the main spring 3 is secured. A dog or restraining pawl 33 40 is arranged in the base 2^a to lock the gear 32 against rotation in one direction so that the spring may be held under tension. A transmission mechanism and an electric generator associated therewith substantially as 45 above described is arranged in the upwardly extending body or shell 2, which is provided with a reduced neck 2^b upon the upper end of which is mounted an electric lamp 34 to which the lead wires 11 and 12 from the 50 generator are extended.

In the flash lamp form of the invention of Fig. 1, the generator is operative only while released from the control of the brake by the pressure, constantly, of the finger of the operator on the push button 24, which, however, represents but one form of brake control. Another form of brake control is shown in Fig. 2 as comprising a push button 25 slidable in the casing or shell 2 to remain in a given position as long as may be desired without pressure on the button and thus serve to apply the brake 22 to the rotor of the generator. Thus, the shifting of the push button 25 in one direction serves to apply the brake and hold it until the push button is again shifted in the opposite direction. It is understood that a compound spring, that is, a spring formed of a plurality of single springs in combination, may be employed instead of the single spring shown.

What is claimed is:

1. In a generating set adapted to be operated by manual power, a tubular casing adapted to be grasped by the hands of the user, and means for generating electric power comprising a spring arranged to be manually wound, and a generator encased within the casing having relatively rotatable, coaxially arranged field and armature structures, these parts being displaced from each other in an axial direction and having opposed plane faces, the dimensions of these parts being such that they extend in a radial direction substantially to the inner wall of the casing.

2. In a device of the class described, the combination of a casing; a frame therein; field coils fixedly secured to said frame with their cores parallel to the axis of said casing; a lamp secured to one end of said frame; electric connections between said coils and lamp; a shaft in bearings on said frame; a magnet on said shaft with the end faces of its poles opposed and adjacent to the ends of said cores; and means for rotating said magnet.

In testimony whereof, I have hereunto set my hand.

GEORGE B. COLEMAN.
